UNITED STATES PATENT OFFICE.

HALCOLM ELLIS, OF EAST ORANGE, NEW JERSEY.

NUMBER PRINTING AND PUNCTUATING MECHANISM.

1,197,277.

Specification of Letters Patent. Patented Sept. 5, 1916.

Original application filed December 30, 1908, Serial No. 470,108. Divided and this application filed July 9, 1913. Serial No. 772,093.

To all whom it may concern:

Be it known that I, HALCOLM ELLIS, a citizen of the United States, residing at East Orange, county of Essex, and State of New Jersey, have invented certain new and useful Improvements in Number Printing and Punctuation Mechanisms, of which the following is a specification.

This invention relates to number printing and punctuation mechanism.

The present application is a division of my application on combined adding machines and typewriters, filed December 30, 1908, Serial No. 470,108.

One object of the invention is to provide improved printing mechanism for adding and listing machines which will possess great manifolding ability and will provide for permanent alinement both in the listing of numbers and in the printing of totals.

Another object is to provide printing mechanism of the rotary or pivoted sector type as an improvement on the printing mechanism set forth in my Reissue Patent No. 12528, dated August 28, 1906, which will provide for automatic rebounding of the type sectors immediately after they have made their impression on the paper, thereby preventing chattering of the type or double printing.

The invention has for a further object the provision of novel means for the punctuation of the numbers printed by the printing mechanism and adapted for regulation or adjustment for printing characters representing United States money, or to be instantly changed to print in plain units, or, to print in plain units with decimals or tenths.

A further object is to provide novel means whereby the punctuation in discounting operations may be regulated, or, the printing may be cut out entirely so that the machine on which the printing and punctuating mechanism is used can be operated for addition or multiplication without printing the series of operations upon the paper.

In the following description and accompanying drawings I have set forth a construction adapted to carry out the foregoing objects and which discloses the mode of operation of the invention, but I do not restrict myself to the details of construction set forth, as I am aware that modifications of structure may be resorted to in carrying

out the invention without departing from its mode of operation.

In the accompanying drawings:—Figure 1 is a vertical longitudinal section through the mechanism for the addition and printing of numbers, certain parts being omitted, but enough of the machine set forth in my application Serial No. 470,108, filed December 30, 1908, being shown to disclose the coöperation of the present improvements therewith, the parts being shown in normal position; Fig. 2, a similar view showing the parts with one numeral key depressed and the adding and printing mechanism in position just prior to printing; Fig. 3, a vertical longitudinal detail section of the numeral printing mechanism, the parts being in position for printing; Fig. 4, a view similar to Fig. 3, with the parts in their restored position; Fig. 5, a view like Fig. 3, showing the type after rebounding from the paper, the punctuation printer being in printing position; Fig. 6, a right-hand elevation of the numeral printing mechanism, showing its relation to other elements; Fig. 7, a detail front elevation of the punctuation slide; Fig. 8, a perspective view of the punctuation slide; Fig. 9, a detail front elevation showing the method of operating the "0" printing triggers from the left; and Fig. 10, a right-hand elevation of the numeral printing mechanism and certain other parts, the printing mechanism being in printing position.

Operation of racks and stops for same.—The machine is operated through suitable means, not shown, by a handle or power means acting on shaft O1.

Referring to Figs. 1 and 2, R50, is one of the racks, of which there are a plurality, having a long piece extending from the front end of the keyboard back to the adding wheels, A50. The rack R50, slides back and forth in the machine on the rod K3, extending across the machine under the keyboard and past the crossbar R92, at the rear end of R50; both the rod K3, and the bar R92, being provided with suitable grooves in which the rack R50, can slide, the grooves serving as guides to maintain the rack R50, in its vertical position. On the top and bottom of the rack R50, are gear teeth 50R, which properly mesh with the gear teeth in the small gear wheels A50 of the accumulator, when the same are brought into engage-

ment with the rack R50. On the upper side of the rack R50, beginning near the front end, are a series of stops which serve as the abutting surfaces to engage stops K23, mounted on the numeral keysystems K51; K52, to K59. These keysystems K51, to K59, are normally held in the positions shown in Fig. 1 by means of the springs K80. The location of the various steps on the upper side of the rack R50, is so arranged that each step engages a particular one of the stops K23, on one of the nine keysystems K51, to K59, and being arranged vernier fashion, the engagement of the rack R50, with any stop K23, will permit of a definite amount of sliding movement of the rack R50. For instance, the engagement of the rack R50, with the stops K23, on the keystem K51, would permit the rack R50, to move to the rear a distance of one of the teeth 50R. If, for instance, the keystem K54, was depressed, as shown in Fig. 2, and the rack moved to the rear until it engages the stop K23, on keystem K54, there would be a movement of four teeth 50R, past the bar R92. If at this time the adding wheel A50, is brought into engagement with the rack R50, as shown in the upper wheel of Fig. 2, and the rack R50, is then restored to the position shown in Fig. 1, the upper adding wheel A50, will be rotated a distance of four teeth. If, by a subsequent similar operation, any amount greater than five was added, suitable carrying devices are connected to the adding wheels A50, to cause the wheel in the next column to the left to rotate a distance of one tooth.

Connections between racks and type sectors.—Mounted on the shaft R1, located above the rack R50, is a three-armed lever R45, of which there are as many as the type sectors P54—one arm extending forward and provided with a small, round pin R15, near its extreme end. The arm extending to the rear is provided with a similar pin 15R, and the third arm extending downward is provided with two terminals to which is secured a segmental rack R52, by pins R13, and R14. The pin R14, extends to the left side and engages a vertical slot in the lower side of the rack R50, as clearly shown by the dotted lines both in Figs. 1 and 2, so that any movement, backward or forward, of the rack R50, would cause a rotation about the shaft R1, of the three-armed crank R45, corresponding in extent to the extent of the travel of the rack R50. From the rear arm of R45, a connecting link P53, extends from the pin 15R, to a pin P10, in the type sector P54. This type sector is pivoted at P11, so that it can be rotated in a vertical direction, there being ten positions in which the rack R50, can be located, there are correspondingly ten type on the type sector P54. Inasmuch as the pivot

P11, is connected to an arm 52P, which can swing about the shaft P1, it is evident that after the type sector P54, is swung upward until the proper type comes into position, that a movement of the arm 52P, about P1, in the direction of the platen S would cause the type of the type sector to strike the platen S and print thereon. This position is indicated in dotted lines in Fig. 1 and in full lines in Fig. 3. The alinement of the type is dependent upon the location of the rack R50, and a more accurate stop than K23, on the keysystems K51, to K59, is desirable, therefore, a bar R93, called the alining bar, is mounted upon arms R44, secured to a shaft R2, and just prior to the time when the printing is to take place, the alining bar is raised and enters between the teeth of the sector R52. This brings the three-armed crank R45, to a definite location within the limits of the lost motion between the connecting link P53, and the pins 15R, and P10, and as there are nine of these type sectors and nine levers R45, the alining bar R93, will bring all of the type to a constant alinement. After an operation of adding has been performed, or a series of these operations, and it is desired to take a total, the wheels A50, are first brought into engagement with the rack R50, and the racks are moved backward until the wheels come to their starting point in a manner usual in this class of machines—which operation causes the type to be set according to the accumulation on the adding wheels A50.

To the shaft R1, there is secured a bail 45R, which extends across the machine under the racks R50, as clearly shown in Figs. 1 and 2; and extending across between the sides of the bail 45R, there is a bar R51, which serves as the fastening for one end of the springs R81. A segment R54, is secured to the side arm of the bail 45R, and swings in a path which prevents the alining bar R93, from engaging the teeth of the sector R52, until 45R, is in its extreme rear position, as shown in Fig. 2.

To the head of the rivet R13, there is secured one end of the spring R81, and on one side of the lower arm of R45, there is a pin R16, which serves as a fastening for one end of the coil spring R80, the other end of the spring being secured to a vertical horn, extending up from the rack R50, as clearly shown in Figs. 1 and 2. One of these three-arm cranks R45, is provided for each of the racks R50, the lower arm, in each case, extending down vertically alongside of the rack R50, and the horizontal arms to the front and rear converge to the width of the nine printing type of the printing section in the manner usual in this class of machines.

Number printing device.—The printing

device is mounted between two plates P50, and P51, (see Figs. 1, 2, 3, 4 and 5), which plates are secured in the machine directly above the series of three-arm cranks R45. 5 Passing between these plates is a shaft P1, upon which are mounted a series of upwardly extending arms 52P. To the upper end of the arms 52P, there is pivoted about the rivet P11, the type sector P54, as clearly shown in Figs. 1 and 2. These type sectors have a series of ten figures, from 0 to 9, on their peripheries, and a second rivet P10, serves to connect the upper end of a connecting rod P53, which extends to and engages the pin 15R, on the rear end of the three-armed piece R45. From this, it will be seen that if the rack R50, moved to the rear, then it will, through the vertical slot in its lower sides, move the pin R14, and so 20 swing the piece R45, about the shaft R1, and cause the pin 15R, in the rear of arm R45, to swing through an approximate vertical arc. The distance the pin 15R, will travel will be exactly proportional to the 25 distance the rack R50, travels: thus, if the rack R50, is in its forward position, the pin 15R, would be in its lowest position, and the type sector P54, will be in a position to cause its upper type to print. This 30 type will be "0". If, however, the rack R50, moves to the rear so as to engage the stop K23, on the key stem K51, it will have moved one-ninth of its possible travel and the pin 15R, will be moved upward a small 35 distance. This distance, however, is sufficient to bring the next succeeding type on the type sector P54, to the position of printing, and it will be figure "1". This position is indicated in dotted lines in Fig. 1. If 40 the rack R50, moves to the rear until it engages the stop K23, on the key stem K54, it will swing the type sector P54, upward until the fifth type or figure "4" will come to the printing position, as indicated in Fig. 45 2. Secured to the shaft P1, there is a piece P58, which piece serves as a fastening for one end of the springs P85, the other end of which engages the upward extending arms 52P. Across the upper part of the piece 50 P58, there extends a bar P17. Alongside of each of the arms 52P, there is a flat piece P62, mounted to swing on the shaft P1, the same as the arm 52P. These two pieces 52P, and P62, are held together by means of 55 a rivet P16, and a loop spring P86, which is secured to the piece P62, at both ends and presses against the rivet P16, as clearly shown in Figs. 1 and 2. This piece P62, has on its forward edge three projecting lips 60 for engaging various devices for holding the arms 52P, in its non-printing position. The lowest of these lips engages the printing trigger 57P, which printing trigger disengages the pieces P62, at every operation 65 of the handle. The printing trigger 57P, extends entirely across between the plates P50, and P51, and engages all nine of the pieces P62,—it is secured to a shaft P2, on the right-hand end of which is mounted a piece P73, (see Figs. 6 and 10) outside the 70 right-hand plate P50. This piece P73, is connected through a round hole in P50, to the printing trigger 57P, by a pin 28P, and is provided with a rearward projecting member having an adjusting screw 22P, for 75 engaging an arm P74, mounted on the shaft P1. The relation between the arm P74, and the piece P73, is such that the shaft P1, turns the piece P58, from the position shown in Fig. 1, to the position shown in 80 Fig. 2 before P74, engages the screw 22P, and causes the piece P73, to be moved and the printing trigger 57P, to disengage the pieces P62. A suitable spring P83, Figs. 6 and 10, returns P73, and the printing trigger 85 57P, to their engaging positions. The middle lip on P62, is for the engagement of the "0" printing trigger P57. The triggers P57, are held in engagement by the light springs P82, and are normally in engagement with the piece P62; when, however, the three-arm crank R45, is moved from its position of rest, as shown in Fig. 1, the pin R15, on its forward arm engages the "0" printing trigger P57, and moves 90 P57, to a position out of engagement with the piece P62, as shown in Fig. 2. The upper end of the "0" printing trigger P57, is provided with a wing extending to the left and engaging the next succeeding similar trigger so that when any one of the "0" printing triggers P57, is operated by means of the pin R14, it causes all of the other triggers P57, to the right to become 95 disengaged from the pieces P62. The detail drawing Fig. 9 clearly shows this feature. The upper lip on the piece P62, is for engagement with a horizontal sliding piece P67, which piece P67, is operated by hand and is normally not in position to engage the piece P62. Across the space between the two side plates P50, and P51, of the printing section, there extends a rectangular bar P18, on arm P69 which is 100 adjustably mounted to move a small distance back and forth—this adjustment being accomplished by eccentric shaft P19. This bar is known as the rebound bar. 105 The operation of this printing device is as follows: Assuming that the horizontal slide P67, is put in its non-operating position: First, the parts would be in the position shown in Fig. 1, key K54, being depressed and the handle operated on its forward stroke, the "0" printing trigger P57, 110 would first be disengaged as shown in Fig. 2. Next, the printing trigger 57P, would be operated and the parts would assume the position shown in Fig. 3, at which position the type would strike the paper on the platen 115 120 125 130

"S". In this position, the small pin P16, would be moved away from its contact with the piece P62, which would slightly extend the rebounding spring P86—the piece P62, being in contact with the rebound bar P18; the spring P85, having contracted and moved the type sector P54, from its normal position to its printing position. Inasmuch, however, as the spring P86, is much stronger than the spring P85, the type sector P54, would immediately, after printing, assume the position, shown in Fig. 5, with the type slightly withdrawn from the contact with the paper on the platen "S", thus preventing chattering of the type or double printing. The return stroke of the handle of the machine would cause the shaft P1, to be turned in a reversed direction, and the bar P17, would press against the piece P62, and restore the printing device to the position shown in Fig. 1.

The punctuation device.—By means of this device, the punctuation of the numbers printed by the printing device just described can be so regulated that the machine will print in United States money, instantly changed to print in plain units, and also to print in plain units with decimals. It has a further function of regulating the punctuation in discount, and a further function of cutting off the printing entirely so that the machine can be operated for addition or multiplication without printing the series of operations upon the paper. This device is fully illustrated in Figs. 1 to 8 inclusive. In Fig. 1, this device is shown in its normal position and consists of an arm P59, pivoted at P14, to the arm 52P. This arm P59, terminates at its rear end in a type either a comma or decimal point. P59, has a downward extending member terminating in a flattened foot and having a downwardly projecting lip at its forward end. A third member extends radially from the pivot P14, in an upward direction and is for the purpose of engaging the stationary restoring bar P27. A spring P80, is mounted in a suitable holder P13, on the arm 52P, and has a tendency to turn the piece P59, so that the decimal point will move upward. A hook 61P, is pivoted at P15, to the arm 52P, in such a manner that its rear end can engage the foot on the lower end of P59. This is clearly shown in Fig. 1. The hook 61P, has a tail extending forward, which tail comes into contact with a sliding piece P67. This sliding piece P67, is shown in detail in Fig. 8, and is provided with three humps a, b, c on its upward extending edge. The tail of the hook 61P, normally presses against the flat part of this upper edge, but when P67, is moved laterally so that one of the humps a, b, or c engages the tail of the hook 61P, it raises this tail and so depresses the hook, thereby permitting it to disengage

the rear end of the foot on piece P59, as is clearly shown in Fig. 4; and as the arm 52P, moves the type sector P54, toward the platen "S", the radial tail on the piece P59, would leave the bar P27, and permit the spring P80, to swing the type on the rear end of P59, to the printing line, and this is determined by the lip on the forward end of the foot at the lower end of P59, engaging the hook 61P, as shown in Fig. 5. These three humps a, b and c on the upper edge of P67, are so spaced that they disengage the hooks 61P, mounted on the arms 52P, which would correspond to the punctuation in the number 1,000,000.00 when the piece P67, is in its normal position. If, however, the piece P67, which slides across between the plates P50, and P51, is moved to the right one space, it would bring the three humps a, b and c, one place to the right, and the punctuation would be as in the number 10,000,000.0 This will provide a punctuation with one decimal place, instead of two as is used in United States money. If P67, is moved still farther to the right to its extreme position, then the three humps a, b and c will disengage the hooks 61P, so that the figures will be punctuated as follows 100,000,000. In each of the examples given, the entire series of nine printing devices are used. Of course, if the figure printed does not embrace nine figures, only those punctuating devices will print which are on the released arms 52P. The slide P67, is provided with a series of small holes "d", into which a spring detent P81, (Figs. 9, 10) engages and a small knob 10B, is mounted on the outside of the case on a suitable slide 10B' with an index, (Fig. 7) and engages the slide P67, and enables the operator to locate it laterally. When the tail of the hook 61P, rests against the flat part of the slide P67, it does not disengage the foot on the piece P59, with a consequence that when printing takes place, the type on the rear end of P58, assumes the position shown in Fig. 3, and does not come in contact with the paper about the platen "S". When the arm 52P, is restored to its normal position, the upper extending member of P59, engages the stationary bar P27, and restores the arm P59, to the position shown in Figs. 1 and 2. When it is desired to use the adding mechanism of this machine, without operating the printing device, the small knob 10B, is moved to the left until the index point on its slide comes opposite the letter "X". This causes the lower part of the slide P67, to come into the path of the upper lip on the piece P62, as clearly shown in Figs. 1 and 2, in which position P67, serves as a stop which would prevent any movement of the piece P62, in a rearward direction through the action of the springs P85, and this irrespective of the operation of the printing

hook 57P, or the "0" printing trigger P57, so that multiplication can be performed on the adding device or any other calculation desired, without in any way affecting the 5 record as printed on the paper, and when it is desired to print the result of these computations, it is only necessary to return the knob 10B, to its normal position or such position as is desired.

10 *Discount.*—Whenever it is desired to figure a discount or do any other calculation which involves the multiplication of one number by a number terminating in a decimal fraction, thereby causing it to become 15 necessary to place the decimal point as many figures to the left of the normal position as there are figures to the right of the decimal point in the multiplier, the knob 10B, is moved to the left until the pointer comes 20 opposite the figure on the scale corresponding to the number of decimal places so pointed off. This results in moving the slide P67, to the left, and progressively moving the three humps *a*, *b* and *c* to the left as 25 many of the printing segments as there are places which we wish to count off. The lower projecting edge of the slide P67, which has the detent holes "d", in it proceeds to intercept the right-hand type sectors by 30 engaging the pieces P62,—the distance from the edge of the piece P67, which engages the arms P62, to the hump "c" always representing two of the type sectors. Thus, if 35 it is desired to obtain the net amount after deducting 6% from \$2,436.75, this amount would be multiplied by 94 in the usual way giving a result of \$229,054.50, but, by moving the knob 10B, two places to the left, we 40 cut off the right-hand "5" and "0" and move the punctuation two places to the left so that the figure printed as the net amount is \$2,290.54. By this method, any amount less than one cent is disregarded in the final result. Of course, if there are more than two 45 figures to the right of the decimal point in the multiplier, the knob 10B, would be moved farther to the left so that the pointer comes opposite the third figure or fourth figure of the scale, and it will be seen that the 50 capacity of the machine would extend up as high as eight figures, as shown by the following examples:

123,456,789
55 12,345,678.9
1,234,567.89
123,456,78
12,345,67
60 1,234,56
123,45
12,34
1,23

Printing in units with punctuation slide P67 in the position shown in Fig. 7.
Printing with slide P67, moved one place to the left.
Printing with slide P67, moved two places to the left.

Printing with slide P67, moved three places to the left, eliminating the first figure on the right. Each time the slide P67, is moved one place to the left, the right hand figure is eliminated and the punctuation is moved over one place to the left, as shown.

65 Having thus described my invention, what

I claim as new and desire to secure by Letters Patent, is:—

1. The combination with a number printing device, of punctuation means therefor adapted to be set at will to print at a single operation different predetermined variations of a plurality of punctuation characters for a given number printed by said printing device. 70

2. The combination with a number printing device, of punctuation means therefor adapted to be set at will to print at a single operation different predetermined variations of a plurality of punctuation characters for a given number printed by said 80 printing device substantially simultaneously with the printing of the number.

3. The combination with a number printing device, of means adapted to be set successively at will to print successive predetermined and constant progressively advancing punctuations of the figures printed by the 85 number printing device.

4. The combination with a number printing device, of means adapted to be set at will to print a predetermined and constant progressively advancing punctuation of the figures printed by the number printing device, and a progressive elimination of decimals of the said number. 90

5. The combination with a number printing device, of punctuation means therefor adapted to be set at will so as to be entirely inoperable, or, to print at a single operation different predetermined variations of punctuation of a given number printed by said 100 printing device.

6. A printing mechanism comprising a movable type carrier, a rebound member movable in relation to said type carrier, a rebound device co-operating with the type carrier and rebound member, a spring separate from the rebound device which actuates the type carrier to cause printing, said spring being of less strength than the rebound device, and means for arresting the movement of the rebound member, whereby, after said spring has caused printing to occur by the advance by momentum of the type carrier, said rebound device immediately retracts the type carrier. 110

7. A printing mechanism comprising a movable type carrier, a pivoted arm, a rebound member movable independently in relation to said pivoted arm and pivoted concentrically thereto, a rebound spring constituting the sole connection between the type carrier and the rebound member, means for advancing the type carrier and rebound member, and means for arresting the rebound member to cause the type carrier to rebound immediately after printing occurs. 120

8. A printing mechanism comprising a movable type carrier, a rebound member movable in relation to said type carrier, a 125

rebound spring constituting the sole connection between the type carrier and the rebound member, a spring for advancing the type carrier to cause printing, a latch or trigger adapted to hold the rebound member, and hence the type carrier, in retracted position, and means for arresting the movement of the rebound member, said rebound spring being stronger than the type-carrier-
10 propelling spring, and adapted to cause the type carrier to rebound immediately after printing occurs.

9. In a number printing device wherein a plurality of characters are printed at one time, a punctuation printer consisting of movably mounted type independent of the number printing type, means for maintaining the punctuation printer either in or out of position to print, and means for causing the 20 same to print when in printing position.

10. In a number printing device wherein a plurality of characters are printed at one time, a punctuation device consisting of a punctuation type movably mounted and independent of the number printing type, means for moving the punctuation type into position to print, means for causing the punctuation device to print when in printing position, and restoring means for withdrawing 30 the punctuation device from the printing position.

11. In a number printing device wherein a plurality of characters are printed at one time, consisting of a series of type carriers, 35 each provided with a plurality of type, a punctuation device consisting of a punctuation type movably mounted and independent of the number printing type, means for moving the punctuation type into printing position, means for causing the punctuation type to print when in printing position, and restoring means for withdrawing the punctuation type from the printing position after printing.

40 12. In a number printing device wherein a plurality of characters are printed at one time, a printing device consisting of a series of type carriers, each provided with a plurality of type, a series of punctuation type 45 movably mounted and independent of the number printing type, and operating between the number printing type, means for moving the punctuation type into printing position, means for causing the punctuation type to print when in printing position, and restoring means for withdrawing the punctuation type from the printing position after printing.

13. In a number printing device wherein 50 a plurality of characters are printed at one time, a printing device consisting of a series of type carriers, each provided with a plurality of printing type, a series of punctuation type movably mounted and independent of the number printing type, and operating between the number printing type, means for moving the punctuation type into printing position, means for causing the punctuation type to print when in printing position, and restoring means for withdrawing the punctuation type from the printing position after printing.

55 ent of the number printing type, and operating between the number printing type, and means for causing some of the punctuation type to move to the printing position while others remain out of the printing position, means for causing the punctuation type to print when in printing position, and restoring means for withdrawing the punctuation type from the printing position after printing.

14. A printing mechanism comprising a plurality of type sectors, means for supporting each type sector independent of the others, means for rotating the type sectors until the desired type come to the printing line, means for causing the type sectors to print, a series of punctuation printing devices operated to print at the same time with the type sectors, means for setting such of the punctuation type as it may be desired to have print, and means for withdrawing 85 the type sector and the punctuation type after printing.

15. A printing mechanism comprising a plurality of type sectors, means for supporting each type sector independent of the others, means for rotating the type sectors until the desired type come to the printing line, means for causing the type sectors to print, and a series of punctuation type pivotally mounted on the type sector supports, 95 to be moved to print at the same time the type sectors print.

16. A printing mechanism comprising a plurality of type sectors, means for supporting each type sector independent of the others, means for rotating the sector until the desired type come to the printing line, means for causing the type sectors to print, a series of punctuation type pivotally mounted on the type sector supports, means for 105 causing some of the punctuation type to print while others are withheld from printing.

17. A printing mechanism comprising a plurality of type sectors, means for supporting each type sector independent of the others, means for rotating the sectors until the desired type come to the printing line, means for causing the type sectors to print, a series of punctuation type—one for 110 each sector—arranged to be moved to print at the same time the type on the type sector prints, and means for withholding some of the punctuation type from printing.

120 18. A printing mechanism comprising a plurality of type sectors, a pivoted arm for supporting each type sector independent of the others, means for rotating the type sectors until the desired type come to the 125 printing line, means for causing the type sectors to print, a series of punctuation type normally withheld from printing posi-

tion, and means for causing some of the punctuation type to be moved to the printing position while others are withheld.

19. A printing mechanism comprising a plurality of type sectors, a pivoted arm for supporting each type sector independent of the others, means for rotating the type sectors until the desired type come to the printing line, means for causing the type sectors to print, a series of spring actuated punctuation type normally withheld from the printing position, and means for releasing certain of the punctuation type whereby they are positioned to print at the same time as the type sectors.

20. A number printing mechanism comprising a plurality of type sectors, a pivoted arm for supporting each type sector independent of the others, means for rotating the type sector until the desired type come to the printing line, means for causing the type sectors to print, a series of spring actuated punctuation printers, pivotally mounted on the type sector supports, hooks for engaging the punctuation printers and holding them in non-printing position, and means for releasing certain of the punctuation printers so that they may print while others are retained in their non-printing position.

21. In a number printing device, where a plurality of characters are printed at one operation, a punctuation device consisting of a series of punctuation type movably mounted and independent of the number printing type, a mechanism for setting the punctuation type for printing the punctuation of figures, means for causing the punctuation device to print, and means for withdrawing the punctuation device from the printing position after printing.

22. A number printing device wherein a plurality of characters may be printed at one operation, a punctuation printing device consisting of punctuation printers movably mounted and independent of the number printing mechanism, means for setting the punctuation device for causing certain of the punctuation printers to print, the others being withheld from printing, and means for changing the setting of the punctuation printers.

23. A number printing device wherein a plurality of characters may be printed at one operation, a punctuation printing device, means for setting the punctuation type so that any numbers printed by the number printing device will be punctuated according to one system, and means for changing the setting of the punctuation device to cause numbers printed by the number printing device to be punctuated according to a different system.

24. A number printing device wherein a

plurality of characters may be printed at one operation, a punctuation device consisting of a series of punctuation type movably mounted and independent of the number printing type, means for setting the punctuation type so that any number printed will be punctuated as United States money, means for withholding certain of the number printing devices from printing beginning on the right, and means for moving the punctuation setting mechanism one place to the left for each number printing type so withheld.

25. In a number printing device wherein a plurality of characters may be printed at one operation, a series of type carriers each carrying a plurality of type, means for moving the type carriers until the desired type come to the printing line, a punctuation device consisting of a series of punctuation type movably mounted and independent of the number printing type, means for setting the punctuation type so that any number printed will be punctuated as United States money, means for withholding certain of the number printing type carriers from printing beginning on the right, and means for moving the punctuation setting device one place to the left, for each of the number printing type carriers withheld from operating.

26. In a number printing device, a plurality of independent type sectors, pivoted arms on which they are pivotally mounted, means for rotating the type sectors until the desired type come to the printing position, means for causing the type to print, a punctuation printing device consisting of a series of punctuation type pivotally mounted upon the supporting arm for the type sectors, hooks for retaining the punctuation type both in printing and non-printing positions, a laterally sliding bar, cams thereon for engagement with the hooks, and for setting the punctuation type to move from their non-printing to their printing positions, when the type sectors move toward the platen for printing.

27. A number printing mechanism consisting of a series of type carriers each provided with a plurality of type, means for causing the type to print, a movable member settable at will for engaging the means for causing the type to print and adapted for withholding the same from operating, and means for causing the movable member to engage the type operating members one at a time, beginning at the right.

28. A printing mechanism comprising a series of type sectors, pivoted arms for supporting said type sectors, means for rotating said type sectors until the desired type come to the printing line, springs for causing the pivoted arms to move the type to

print, punctuation type pivoted to the supporting arms, hooks for engaging the punctuation type and holding the same out of the printing position, and a sliding bar having cams thereon for engagement with the aforesaid hooks and causing the hooks to release the punctuation type and permit them to move to their printing position.

29. The combination, with a number printing device, of selectively controlled punctuation means adapted for printing at a single operation any one of several different predetermined arrangements of a plurality of punctuation characters for the number which is printed.

30. The combination with a number printing device, of punctuation means adapted for printing at a single operation a plurality of punctuation characters for the number which is printed.

31. In a number printing device wherein a plurality of characters are printed at one operation, punctuation printing means selectively controlled at will adapted for punctuating at one operation the number which is printed.

32. In a number printing device wherein a plurality of characters are printed at one operation, means controllable at will for printing a punctuation of the number which is printed.

33. In a number printing device wherein a plurality of characters are printed at one operation, selectively controlled punctuation means adapted to print at a single operation a predetermined plurality of punctuation characters for the number which is printed.

34. In a number printing device wherein a plurality of characters are printed at one operation, selectively controlled punctuation means adapted for printing at a single operation any one of several different predetermined arrangements of punctuation characters for the number which is printed.

35. In a number printing device wherein a plurality of characters are printed at one operation, a punctuation printer comprising movably mounted type independent of the number printing type, and means for causing the punctuation type to print.

36. The combination with a type carrier, of a rebound member movable in relation thereto, a rebound spring-device co-operating with the rebound member, and the type carriers so that they are adapted to move as a unit to cause printing to occur, and means independent of the rebound member and rebound spring-device adapted to actuate the type carrier.

37. A printing mechanism comprising a

rockably mounted type carrier, pivoted means for causing the type carrier to advance from normal position to printing position, a rockably mounted rebound member movable in relation to said type carrier, and rebound means co-operating with the type carrier and rebound member adapted to cause said type carrier to automatically rebound after printing has occurred and prior to retraction of the type carrier to its normal position.

38. A printing mechanism comprising a rockably mounted arm, a type carrier having different indicia which is pivoted to said arm, means for setting the type carrier in different positions so that it will print the desired indicia, means for rocking said arm and type carrier to cause printing to occur, and a rebound spring independent of the setting means and said type carrier which co-operates with said arm and is adapted for causing said arm and type carrier to automatically rebound after printing has occurred.

39. A printing mechanism comprising a movable type carrier, having different indicia, means for setting the type carrier in different positions so that it will print the desired indicia, means for causing said type carrier to advance to cause printing to occur, a rebound member movable in relation to said type carrier, a rebound device independent of said setting means, co-operating with the type carrier and rebound member adapted to cause rebound of the type carrier after printing has occurred, and means for arresting the movement of the rebound member to cause the type carrier to rebound immediately after printing occurs.

40. A printing mechanism comprising a movable type carrier, having different indicia, means for setting the type carrier in different positions so that it will print the desired indicia, means for causing said type carrier to advance to cause printing to occur, a rebound member movable in relation to said type carrier, a rebound spring independent of said setting means, co-operating with the type carrier and rebound member adapted to cause rebound of the type carrier after printing has occurred, and means for arresting the movement of the rebound member, whereby the rebound spring will cause the type carrier to rebound immediately after printing occurs.

In testimony whereof, I hereunto affix my signature in presence of two witnesses:

HALCOLM ELLIS.
